ASH TRAY

Robert L. Carruthers, Denver, Colo.

Application September 19, 1955, Serial No. 37,984

Term of patent 14 years

(Cl. D85—2)

FIG. 1.

FIG. 2.

FIG. 3.

FIG. 4.

Fig. 1 is a top plan view of an ash tray embodying my new design;

Fig. 2 is a side elevation of the ash tray of Fig. 1;

Fig. 3 is a vertical section taken along line 3—3 of Fig. 1; and

Fig. 4 is a vertical section taken along line 4—4 of Fig. 1.

The essential feature of my new design is the bridge which extends across the ash tray.

I claim:

The ornamental design for an ash tray, as shown and described.
